TABLE ATTACHABLE SEAT FOR A CHILD

Lawrence A. Hanley, 715 A St.,
Coeur d'Alene, Idaho 83814

Filed Apr. 20, 1972, Ser. No. 246,114

Term of patent 14 years

Int. Cl. D6—01

U.S. Cl. D6—9

FIG. 1

FIG. 2

FIG. 3

FIG. 4

FIG. 5

FIG. 6

FIG. 1 is a side view of a table attachable seat for a child;

FIG. 2 is a front end view of the table attachable seat for a child;

FIG. 3 is a rear end view of the table attachable seat for a child;

FIG. 4 is a top plan view of the table attachable seat for a child;

FIG. 5 is a bottom plan view of the table attachable seat for a child;

FIG. 6 is a fragmentary side view looking at the central bottom portion of the table attachable seat from the line 6-6 on FIG. 4.

I claim:

The ornamental design for a table attachable seat for a child, as shown and described.
